UNITED STATES PATENT OFFICE.

EDMUND GREEN, OF OAKLAND, CALIFORNIA.

ORE-ROASTING FURNACE.

SPECIFICATION forming part of Letters Patent No. 323,666, dated August 4, 1885.

Application filed November 10, 1884. (No model.)

To all whom it may concern:

Be it known that I, EDMUND GREEN, of the city of Oakland, county of Alameda, and State of California, have invented an Improvement 5 in Ore Roasting and Condensing Furnaces; and I hereby declare the following to be a full, clear, and exact description thereof.

My invention consists in the combination of the ore-chamber, the lower and upper flues, 10 the escape-pipe at the rear end of the chamber, the suction-blower in the pipe, the condenser with which the blower communicates, and the air-passage extending within the shell of the furnace, above the chamber, communicating with the open air at the rear of the furnace and with the ore-chamber at its forward end, all arranged as I shall hereinafter 15 fully explain.

The object of my invention is to provide a 20 furnace for treating the sulphuret ores of gold, silver, cinnabar, and tellurium ores of gold, and others containing volatile matters, which is simple and cheap in construction and effective in operation.

25 Referring to the accompanying drawings, Figure 1 is a longitudinal vertical section of my furnace. Fig. 2 is a vertical cross-section of the same.

A is the furnace, having at one end the fire-door B, by which access is obtained to the fire-box C. This fire-box is in direct communication with a flue, D, which extends at an upward inclination to the rear end of the furnace, and there, by an upward bend, connects with 30 a return-flue, F, extending to the front end of the furnace at a downward inclination and opening into the smoke-stack G. Between these two flues is the ore-chamber H, to which access is had by means of suitable doors, h, in 35 the end and doors h' in the sides. The chamber is separate and distinct from the flues, and neither the fumes nor the products of combustion enter the chamber.

40 Hoppers I, passing down through the top of the furnace at its upper or rear end, provide for supplying the charge to the ore-chamber.

45 Opening out of the upper end of the ore-chamber is a pipe or passage, J, communicating with the suction-blower K, which is in 50 communication with a water-tank, L.

In the brick-work of the top of the furnace,

and about on its longitudinal center, is an air-passage, M, the upper or rear end of which is in communication with the outside air, and the lower or forward end communicates 55 through suitable pipes, m, with the forward end of the ore-chamber.

In the drawings herewith shown it will be seen that the lower and upper fire-flues and also the ore-chamber are divided into two 60 parts longitudinally; but this construction is a mere matter of convenience, and is not essential to the operation of the furnace, which is as follows: The ore is fed through the hoppers I until the ore-chamber H is completely 65 charged, the fire is started in the box C, and its flames and products of combustion are drawn back through the lower flue, D, under the ore-chamber, and forward through the upper flue, F, over the chamber, to the front 70 end of the furnace, and pass out through the smoke-stack G. In their course they nowhere come in contact with the charge of ore, which is, however, heated or roasted within its chamber, both below and above, and which is thus 75 kept pure and prevented from vitrifying. The volatile portions or fumes are drawn off by the suction-blower K, through the pipe J, and are forced down into the water-tank L, whereby 80 they are condensed and saved.

By not being mingled with the products of combustion these fumes are kept pure, and the condensed production consequently pure. Instead of admitting cold-air to the roasting-chamber, as is usually done, it will be seen 85 that the air in its course through the passage M is heated to a very high degree, and in that state is drawn into the lower or forward end of the chamber, whereby the ore is prevented from being chilled.

I do not confine myself to the water-tank here shown as a means for condensing the fumes, for any other suitable apparatus may be used, the object being not the means by which the fumes are condensed, but the fact 95 of their condensation, by which they are saved without waste and in the purest state.

In working the charge in the chamber H that portion of the ore which is at the forward end, nearest the fire, is raked out first through 100 the end doors, h, as it is completely roasted. Then, by means of the usual hoes inserted

through the side doors, *h'*, the charge is raked down and fresh material is added through the hoppers.

Having thus described my invention, what I claim as new, and desire to secure by Letters Patent, is—

The furnace *A*, having a fire-box, *C*, flues *D*, and return-flues *F*, in combination with the ore-chambers *H*, air-passage *M*, communicating with the open air at the rear end and with the forward end of the ore-chambers through pipes

m, the pipe *J*, communicating with the end of the ore-chamber, the suction-blower *K*, and the condensing-tank *L*, with which the blower communicates, all substantially as herein described. 15

In witness whereof I have hereunto set my hand.

EDMUND GREEN.
